UNITED STATES PATENT OFFICE.

THOMAS HEAD, OF COPETOWN, ONTARIO, CANADA.

GRAINING COMPOSITION.

SPECIFICATION forming part of Letters Patent No. 321,295, dated June 30, 1885.

Application filed March 2, 1885. (No specimens.) Patented in Canada September 30, 1884, No. 20,292.

To all whom it may concern:

- Be it known that I, THOMAS HEAD, a citizen of the Dominion of Canada, residing at Copetown, in the county of Wentworth and Province of Ontario, Canada, have invented a new and useful composition of matter to be used for ornamenting and decorating light-colored painted wood or other material, of which the following is a specification.
- My composition consists of the following ingredients, combined in the proportions stated, viz: tincture of arnica, one ounce; spontaneous fermented vinegar, sixteen ounces; white glue, six grains; pyroligneous acid, one ounce; oil of turpentine, half ounce. These ingredients are to be mixed in the following manner: Put the arnica into the vinegar, dissolve the glue in the pyroligneous acid, mingle by agitation, and then add the oil of turpentine.
- In using the above-named composition, mix the liquid in small quantities with finely-powdered paint of the color desired, rub it on the painted material with a soft brush or a wad of cotton waste, or any kind of an absorbent,

then work out your designs and impressions 25 with india-rubber stamps or dies, or anything that will produce the desired effect, and varnish as soon as dry.

I am not aware of any patent in the United States that would in any way conflict with 30 this, and I believe it to be an improvement on one granted to me in Canada, No. 20,292, dated September 30, 1884, for fifteen years.

What I claim, and desire to secure by Letters Patent of the United States, is—

The herein-described composition of matter, to be used by mixing with mineral and other powdered paints, for ornamenting and decorating light-colored painted wood or other material, consisting of tincture of arnica, spontaneous fermented vinegar, white glue, pyroligneous acid, and the oil of turpentine, 40 mixed in the manner and proportions specified.

THOMAS HEAD.
